UNITED STATES PATENT OFFICE

2,193,059

AMPOULE FILLING MACHINE

Harold Eric Chapman, Maidstone, England

Application December 17, 1938, Serial No. 246,474
In Great Britain October 9, 1937

7 Claims. (Cl. 226—107)

This invention relates to an improved method of and machine for filling with pharmaceutical and medicinal liquids, flasks or bottles having caps or covers of puncturable material, filling being effected by puncturing the puncturable material of the cap by a filling needle through self-sealing punctures made thereby.

The object of the invention is to enable a number of flasks or bottles to be filled simultaneously, the whole of the operation being carried out without risk of manual or air-borne contamination. The machine which is constructed with a view to permitting of sterilization of every part with the machine fully assembled is thus capable of filling solutions, vaccines, serums and similar liquids free of contamination and in an aseptic condition into sterile flasks or bottles.

The improved method of filling and the aseptic filling machine according to this invention are applicable for filling any flask through a puncturable rubber cap, but has a particular application in the filling of vaccine bottles and the like having a cap embodying a filtering medium housed in a chamber having puncturable roof and floor diaphragms as described in my prior United States specification No. 2,061,958, and the particular machine hereinafter described, by way of example, has been designed for the express purpose of filling such capped bottles.

The improved method of filling liquid into bottles through needles piercing puncturable self-sealing caps consists in delivering measured quantities of a liquid by gravity to a battery of burettes and ejecting the liquid under pneumatic pressure through the filling needles.

Broadly, the improved aseptic filling machine comprises a liquid reservoir, a battery of burettes receiving liquid under gravity from the reservoir, valve means controlling the flow of liquid to the burettes, a plurality of filling needles, and valve means controlling the supply of compressed air to the burettes for ejecting liquid therefrom through the needles into bottles whose caps are pierced by the needles.

In accordance with a preferred construction, a plurality of burettes or charge-holding chambers are provided into which a sterile fluid gravitates from a reservoir, charging of the chambers being effected from the bottom upward and the charges of liquid then simultaneously delivered by compressed air admitted to the tops of the burettes through a plurality of filling needles, one for each chamber.

The accompanying drawings illustrate a preferred construction of machine in accordance

with the invention, together with a diagram of the associated liquid and air sterilizing plant.

In the drawings—

Figures 1 and 2 are longitudinal and transverse cross-sectional elevations of the machine. 5

Figure 3 is a sectional plan on line III—III of Figure 1.

Figure 4 is a diagrammatic view of the machine and associated sterilizing plant.

Figure 5 is a section on the line V—V of Figure 6 and showing on enlarged scale a certain valve arrangement used in this invention. 10

Figure 6 is a section on the line VI—VI of Figure 5.

Figure 7 is a longitudinal sectional elevation 15 through two of the burette control taps.

Figure 8 is a cross-section on line VIII—VIII of Figure 7; and

Figure 9 is a sectional plan of the single-handle 20 operating mechanism for simultaneously actuating rows of burette control taps.

The machine is provided with a base 1, supported on levelling screws 2, and comprising a box-like compartment 3 having openings 4 in its opposite ends so as to form a tunnel into which a false-bottom tray 5 containing the capped bottles for filling may be inserted. These tunnel openings 4 are closed by self-levering doors 6 swivelly mounted on hinge bars 7 pivotally supported by the opposite end walls of the base 1. The doors 6 which are secured in the closed position by the swingable screw handles 8 have inwardly projecting tongues 9 which locate the bottle tray 5 in the correct position longitudinally. The tray 5 is correctly located transversely by the engagement of its mouth flange 10 within longitudinal channels 11 formed between the inturned ledges of parallel angle-section strips 12 supported by the mouth flanges 13 of the compartment 3 and the inturned mouth rims of a roof member 14 of 25 inverted tray-form. The bottles 15 are supported within the tray 5 by one of a series of removable floors 16, the depending rims 17 of which are made of various depths so that a floor 16 with a rim 17 of appropriate depth is chosen according to the height of the bottles 15 being filled, in order that the rubber caps 18 are supported with their upper surfaces just below the level of the mouth of the bottle tray 5. The bottles 15 are located in the desired position by an apertured plate 19 supported on pillars 20 having pivoted heads 21 which, when swung over to the position shown in Figure 2, clamp the plate 19 in position. The removable tray floors 16 are each provided with interchangeable feet 22 which are of 30

different sizes according to the depth of the floor rim 17 being used, in order that the soles of the feet 22 are normally just above the open bottom of the tray 5, as shown in Figures 1 and 2. Immediately below each of the tray floor feet 22 is a vertically movable plunger 23 freely slidable within a sleeve 24 depending from the floor 25 of the compartment 3. The plungers 23 have head discs 26 and feet discs 27 with rubber washers 28 to contact with the floor 25 and the lower ends of sleeves 24 respectively. The four plunger feet 27 rest upon a pair of parallel lifting bars 29 suspended on swinging links 30 secured to transverse spindles 31, 32, journaled in the opposite walls 15 of the lower portion 33 of the base 1, one end of spindle 31 projecting out beyond one wall to receive a handle 34. The bottles 15 are equidistantly spaced in two parallel rows by the plate 19 so that when the tray 5 is correctly located by the 20 tongues 9, each bottle is immediately below a hollow filling needle 35 which projects down through an opening in the tunnel roof 14. The needles 35 depend from control taps 36 suspended from a lower deck plate 37 supported by pillars 38 25 upstanding from the base flange 13. The taps 36 in each row are in axial alignment so that the conical plugs 39 may be mounted, as shown in Figure 7, on a common operating spindle 40. Each conical tap plug 39 is provided at its larger end 30 with a diametrical slot 41 to receive a pin 42 piercing the spindle 40 in order that all taps in a row are operated simultaneously as the spindle 40 is rotated. Each tap plug is pressed upon its conical seating within the tap body 36 by a coil 35 spring 43 interposed between the end of the plug 39 and a washer or collar 44 held against axial movement along spindle 40 by a split ring 45. Each tap body 36 is provided with three passages 46, 47, 48 therein, passage 46 extending down to 40 the hollow needle 35, passage 37 extending up to afford an entrance into the bottom of a burette 49 or 50, and passage 48 extending sidewardly to register with the bore 51 of a junction member 52 to which the lower end of a liquid feed pipe 53 45 is connected. Each tap plug 39 has a transverse recess 54 in its periphery to establish communication between passages 46, 47 and 48 at appropriate times, as hereinafter more particularly described. The front ends of the spindles 40 are furnished 50 with tongues 55 adapted to be engaged within transverse notches 56 provided in the rear ends of a pair of stub spindles 57 rotatably journaled in the front wall 58 of a hood or casing 59 supported by the base 1. The stub spindles 57, which 55 pass through fluid-tight glands 60 mounted on the hood wall 58, carry toothed wheels 61 constantly in mesh so that both stub spindles 57, and through them the tap spindles 40, are simultaneously rotated by a single tap control handle 62 60 mounted on a dished cover 63, through a pinion 64 associated with the handle 62 meshing with a pinion 65 on one of the stub spindles 57.

Of the twelve burettes provided, ten of them, designated by numeral 49, are of metal, whilst 65 the remaining two, designated by numeral 50 and situated one at the front end of each row, are made of glass, encased with protective metal sheaths 66 having sight openings 67 so that the contents of the glass burettes 50 may be observed 70 through the lower window 68 in the hood front wall 58. A graduated scale plate 69, common to both burettes 50, is located in front of the sheaths 66 and, since the bores of the burettes 49 and 50 are of identical dimensions, the measured quantity of liquid, as shown by scale 69, within either

of the burettes 50, is a correct indication of the amount of liquid in each burette. The upper ends of the burettes 49, 50 and of the sheaths 66 are connected to headers 70 mounted on an upper deck plate 71, the burettes 49, sheaths 66 and lower and upper deck plates 31, 71 respectively together constituting a rigid structure. Each row of headers 70 has a common pipe 72 passing in fluid-tight manner through the aligned headers 70 via packing glands 73. The interiors of the 10 burettes 49, 50 communicate with the pipes 72 via passages 74, so that sterile air or steam may be passed simultaneously to the interiors of all burettes 49, 50, as hereinafter described. The pipes 72 are connected through passages 75 to the 15 horizontal and longitudinal bore 76 of a main control valve 77 mounted on the upper deck 71. A vertical bore 78 communicates at its lower end via a sleeve 79 with a connector piece 80 to which is connected a pipe 81 extending between the two 20 rows of burettes 49, 50 to an inlet union 82 mounted on the back wall 83 of the hood 59. Supported on pillars 84 above the upper deck 71 is a saddle tank 85 which can receive liquid (from a sterilizing installation hereinafter described) 25 through a connector 86 mounted on the hood wall 83. Liquid from this tank 85 can gravitate through the pipes 53 to feed the burettes 49, 50 via the taps 36. The amount of liquid in the tank 85 is indicated by a gauge glass 87, extending 30 between upper and lower nipples 88, 89 respectively, and visible through a window 90 in the good front wall 58. From the upper nipple 88 depends a pipe 91 which communicates at its lower end with the bore 78 of valve 77. The plug 92 of valve 77 has a three-way passage 93 therein by means of which communication can be established at the appropriate times between the pipe 81 (through connector 80, sleeve 79 and bore 78), pipes 72 (through bore 76) and pipe 81 (through 40 bore 78). The plug 92 has a tongue 94 adapted to engage within a transverse notch 95 in the inner end of the spindle 96 of an exteriorly operable handle 97 by means of which the plug 92 can be turned. 45

A pressure gauge 98 mounted on a connecting pipe 99 passing through a fluid-tight gland 100 in the side wall of the hood 59 is connected to the sleeve 79 below the valve 77. The pipe 81, valve 77 and pipes 72 are normally used for sterile 50 air, so that during normal working air is allowed to leak constantly through a small constant-leak valve 101 mounted on the main valve 77. The cone plug 102 of the valve 101 is adjustable to regulate the degree of leak by screwing in or out 55 the plug 103 engaging in a threaded boss 104 in the wall of the hood 59, said plug 103 being operable exteriorly. A small relief valve 105 is mounted in the wall of the tunnel 3 of the base 1 which is regulated by spring-loading or other 60 means to provide for a constant leak of air from the interior of the tunnel 3, the air in the interior of which is maintained at a predetermined positive pressure, so that no air can pass into the machine when either of the doors 6 is opened. 65 The tunnel roof 14 is provided with perforations 106 to ensure an equalized downflow of air from the hood 59 into the tunnel 3. The side walls of the tunnel 3 and hood 1, and the crown of the latter, are provided with internal ribs 107 to 70 strengthen the machine structure, particularly during periodical steam-sterilizing. A safety valve 108 is mounted on the crown of the hood 59 to prevent excessive pressure building-up within the machine. A drain cock 109 is provided at the 75

bottom of the machine and drainage tubes 110 connect the tank 85 with an outlet union 111 on the back wall of the hood 59. A thermometer 112, mounted between holders 113, 114 on the lower 5 and upper decks 37, 71 respectively, is arranged at the front end of the hood 59 so as to be visible through the window 68. Sterile air and liquid are delivered to the machine from the sterilization plant, shown diagrammatically in Figure 4. 10 This plant comprises a bulk liquid storage tank 120 connected by a valve-controlled branch pipe 121 to a sterile air line 122 emanating from an air filter 123 of suitable design, into which air is introduced under pressure through an air inlet 15 branch 124. The air line 122 is connected to the inlet union 82 on the back of the machine. Liquid, e. g., unsterilized liquid, is elevated under air pressure through the liquid pipe 125 into a primary filter 126 constructed to permit initial 20 sterilization by wet steam, and thence through the pipeline 127 to incorporate a secondary filter 128 (preferably of the sintered-glass type) for removal of fibre and other suspensions emanating from the primary filter, into either one of a pair 25 of containers 129, each capable of holding sufficient sterile liquid for several fillings of the tank 85 of the machine, into which tank 85 the sterile liquid can be delivered from the containers 129 through piping 130 under the pressure of air bled 30 from the pipeline 122. Steam may be fed to either or both the liquid pipe 130 and the air line 122 through a valve-controlled bridge pipe 131. It will be appreciated that in order to maintain the machine in an aseptic condition and prevent contamination of the liquid during the filling process, all parts of the machine which come into contact with the sterile liquid and sterile air must be 35 constructed of non-corrosive material, whilst, as shown in the drawings, pipe bends and the like in which spores or bacteria are likely to lodge and propagate are eliminated wherever possible. The entrance of foreign matter liable to contaminate the components is prevented by the use of highly efficient fluid-tight valves and pipe joints.

40 If the machine is employed for filling bottles through puncturable caps not providing for open communication between the bottle interior and atmosphere as described in my prior United States specification No. 2,061,958, the filling needles 35 are modified to incorporate an air vent. 45 Prior to using the machine and periodically during use, steam at a suitable pressure is admitted for sterilizing to the empty liquid tank 85 through union 86 to drain the tank via tubes 110 and union 111, and thence to the feed-pipes 53 and also to the main valve 77 through union 82 and pipe 81, thence through pipes 72, burettes 49, 50, to taps 36 and needles 35. Steam escapes 55 to the interior of the hood 59 and base 1 through the constant-leak valve 101 and the needles 35, the washers 28 under the head discs 26 of plunger 23 preventing escape through the plunger sleeves 24. The drain cock 109 and, if desired, the air relief valve 105 are closed, so that a suitable pressure of steam is maintained during the sterilizing 60 operation, the building-up of an excessive pressure being prevented by the relief or safety valve 108. After the sterilizing operation, a suitable quantity of sterile liquid is run into the tank 85, the feed pipes 53 being filled at the same time 65 (the plug bodies 39 of taps 36 are at this time in the position shown in Figure 8). The handle 62 is then operated so that the recesses 54 in the tap bodies 39 establish communication between the feed pipes 53 and the bottom of the burettes 49,

50, whilst still closing the passages 46 leading to the needles 35. The gravitating liquid mounts up within the burettes 49, 50 until the required charge is shown by the scale 69, whereupon the taps 36 are again operated by means of handle 5 62 to prevent further supply of liquid from the feed pipes 53. Prior to filling the burettes 49, 50 a tray 5 loaded with capped bottles 15 is introduced through one of the doors 6 into the tunnel 3, within which the tray 5 is located by the door 10 tongues 9, so that by depressing the handle 34, the swinging links 30 elevate the bars 29 and thus move the plunger 23 up through the sleeves 24 of the tunnel floor 25. The ascending plungers 23 contact with the feet 22 of the tray bottom 16 15 and lift same, with the empty bottles 15 a sufficient distance for the fixed needles 35 to pierce right through the caps 18. The caps 18 are constructed with puncturable self-sealing roof and floor diaphragms, as described in my prior United States specification 2,061,958. Whilst the bottles 15 are thus elevated, the taps 36 are operated by handle 63 to establish communication between the filled burettes 49, 50 and the hollow needles 35, and the main air valve 77 is operated by handle 97 to bring the plug 92 thereof to the position shown in Figure 5, in which position sterile air from the pipe 81 can pass into the pipes 72 connected to the tops of the burettes 49, 50, the liquid being thus ejected under pressure through needles 35 into the bottles 15. The appropriate valve movements are then made to prevent delivery of liquid or air to the burettes 49, 50 and of liquid to needles 35, the filled bottles 15 are lowered, the loaded tray 5 removed and another 20 tray of empty bottles introduced, in readiness for the filling cycle to be repeated.

I claim:

1. A liquid filling machine including a fluid tight casing, a liquid reservoir within said casing, 40 a battery of burettes within the casing and connected at their lower ends to said reservoir to receive liquid therefrom, valve means controlling the flow of liquid to the burettes, a plurality of filling needles within said casing each carried by 45 a burette, means for supplying compressed air to the upper ends of the burettes, other valve means controlling the air supply, a bottle carrier within the lower part of the casing to hold bottles in alignment with the needles, and means to raise 50 the bottle carrier and cause the needles to enter bottles supported by the carrier.

2. A liquid filling machine according to claim 1 wherein the liquid flows by gravity to the lower 55 ends of the burettes, and the first mentioned valve means also controls the flow of liquid from the burettes to the needles and the valves are in axial alignment.

3. A liquid filling machine according to claim 1 wherein the first mentioned valve means effects 60 simultaneous filling of all the burettes in one position and simultaneously places all burettes in communication with their needles in a second position.

4. A liquid filling machine according to claim 1 65 wherein the second valve means is provided with a bleeder valve communicating with the interior of the casing to maintain pressure within the casing in excess to the external air pressure.

5. A liquid filling machine according to claim 1 70 wherein there is provided means for admitting sterilizing fluid to said tank and said second mentioned valve means for causing complete filling of the casing and parts therein with sterilizing fluid.

6. In a machine of the class described, a plurality of series of burettes, a valve casing having a valve chamber therein and provided with longitudinal and transverse passages leading from said chamber in both directions, a plug valve mounted in said chamber and having a diametral passage and a passage at right angles to the diametral passage, a fluid supply connection at each end of the transverse passage, and means
- 5

for connecting each end of the longitudinal passage in the valve casing, with a respective series of burettes.

7. The device of claim 6 characterized by having each connecting means between a series of burettes and the valve casing consist of a single continuous tube having a port opening into each burette.

HAROLD ERIC CHAPMAN.
